UNITED STATES PATENT OFFICE

1,973,293

RADIO APPARATUS

John M. Miller, Philadelphia, and Sarkes Tarzian,
Bryn Mawr, Pa., assignors to Atwater Kent
Manufacturing Company, Philadelphia, Pa., a
corporation of Pennsylvania

Application October 23, 1928, Serial No. 314,512
Renewed October 7, 1933

12 Claims. (Cl. 179—171)

Our invention relates to tuned amplifiers particularly as utilized in radio receiving apparatus to select and amplify currents of radio frequency.

In accordance with our invention, in an amplifier, particularly a multi-stage, radio-frequency amplifier, comprising cascaded tuned circuits and interposed vacuum tubes and in which capacities, and particularly inherent or natural capacities, are utilized in a relation effecting or contributing to stability of the amplifier, the voltage transformation ratios of transformers, preferably disposed in output systems of the tubes, are varied as the circuits are tuned to different frequencies to maintain substantially constant the stability of the system and the stabilizing effect of the capacities.

Further in accordance with our invention, and more specifically, a winding, particularly the primary, of one or more of the transformers comprises a section movable with respect to the remainder thereof and to the secondary winding; preferably the movable coil sections are movable in unison with the tuning elements, for example, condensers in shunt to the respective transformer secondaries.

Still further in accordance with our invention, the stabilizing capacities are comprised, at least in part, by capacities between stator elements of the tuning condensers, which inherent capacities vary with change in position of interposed rotor structure, and the change in magnitude of the effective stabilizing capacities is compensated for by the change in the transformation ratio of the transformers.

Further and more specifically, in each of the transformers above described the maximum mutual inductance between the movable or rotatable primary winding section and the secondary winding is less than the mutual inductance between the fixed primary section and the secondary winding to maintain a desired relative poling of the transformer primary and secondary windings for all positions of the movable primary section.

Our invention resides in the method, system, and features of construction and arrangement hereinafter described and claimed.

For an understanding of our invention, reference is to be had to the accompanying drawings in which:

Fig. 1 is a diagrammatic circuit arrangement of radio receiving apparatus utilizing our invention.

Fig. 2 is a fragmentary plan view of apparatus of Fig. 1.

Fig. 3 is a rear, elevational view of parts shown in Figs. 1 and 2.

Figs. 4 and 5 are plan and elevational views respectively, in section of transformer structure.

Fig. 6 is a perspective view of disassociated, component parts of the transformer of Figs. 4 and 5.

Referring to Fig. 1, the radiant energy absorbing structure comprises an antenna D, or equivalent, and the counter-capacity or earth E, connected respectively to an end of resistance R and a contact S slideable along the resistance to vary the amplitude of reproduced signals, generally as described and claimed in co-pending Miller application Serial No. 253,116, filed February 9, 1928. The resistance R is connected in shunt to the primary of an auto-transformer, preferably having a step-up ratio and comprising the untunable input circuit of a coupling tube V as described and claimed in co-pending Miller application Serial No. 263,272, filed March 21, 1928. The grid g of the coupling tube is connected to one end of coil T and the radio-frequency path to the other effective end of the auto-transformer secondary includes the condensers c, c having low impedance to currents of radio frequency connected between conductors supplying current to the filament f of the coupling tube, and ground E, or equivalent.

Inductively related to the primary P1 of transformer T1 in the anode circuit of tube V, is the secondary S1, in shunt with which is connected the tuning condenser K1 for effecting tuning of the input circuit of the amplifier tube VI in whose anode circuit are included the fixed coil P2 and the movable coil p2, serially connected and together forming the primary of transformer T2 whose secondary S2 tuned by variable condenser K2 is comprised in the input circuit of amplifier tube V2.

The fixed and movable coils, P3 and p3, respectively, are serially connected in the anode circuit of tube V2 and constitute the primary of transformer T3 whose secondary S3 shunted by tuning condenser K3 comprises the input circuit of tube V3 which may be utilized to demodulate amplified, radio-frequency current in which case, there is provided the grid-condenser c1 and grid-leak resistance R1. As the detector or demodulator tube V3 shown is of the alternating-current type having a heater h and a uni-potential cathode f, the terminals of grid-leak r are connected to grid g and uni-potential cathode f of the tube. Resistance R6 of 6,000 ohms, for example, shunted by radio-frequency by-pass condenser C6, renders the uni-potential cathode f positive with respect to heater h to reduce hum.

In the anode circuit of the detector tube between the points *e* and *j* may be connected a telephone instrument, or as shown, the primary *P* of an audio-frequency transformer *T* whose secondary is connected in or to the input circuit of an amplifier of one or more stages.

Referring to Figs. 2 and 3, the tuning condensers which as shown are of the type described and claimed in U. S. Letters Patent 1,668,320 to Kent are mounted on metal supporting bracket 1 having a vertical panel 2 and a horizontal ledge 3 to which is attached an extension plate 4 of suitable insulation, as bakelite or other phenol condensation product, carrying mounting brackets 4 for the radio-frequency transformers *T*1, *T*2, etc. and adapted to support tubes *V*, *V*1, *V*2 etc. as claimed in Kent U. S. Letters Patent 1,655,372. Preferably, the rotors of the tuning condensers, which are at ground, or low, potential are mechanically connected by belts 5 passing over drums 6 secured to the shafts thereof to effect their movement in unison by structure similar to that claimed in Kent U. S. Letters Patent 1,668,155. Single dial operation is made possible by the interposition of coupling tube *V* between the antenna and the first tunable circuit as claimed in Miller Patent 1,639,414 granted August 16, 1927.

Between the elements of the input circuits for example, tuning condenser stators, of tubes *V*1 and *V*2 and between like circuits of tubes *V*2 and *V*3, there exists capacities, particularly natural or inherent capacities *k*4, *k*5 which are effective when the transformer windings are relatively reversed, either by the manner of winding, or mode of connection, to effect stability of the tuned, radio-frequency amplifier stages and to suppress completely if desired, regenerative feed-back caused by couplings between the circuits, as for example, or including, capacity between electrodes of the amplifier tubes. In the regeneration, suppression or compensation circuits heretofore utilized which included capacities, physical condensers and/or inherent capacities, the counter feed-back effect varied in magnitude with change in frequency and additionally in apparatus utilizing inherent capacities, the magnitude of the capacities changed due to change in position of the tuning elements. Referring to Figs. 2 and 3, it is apparent that as the position of the grounded rotor of condenser *K*2 interposed between the stators of condensers *K*2 and *K*3 is changed, the effective, natural capacity between is changed.

To maintain substantially constant the relation between feed-back and counter feed-back effect, and if desired, to maintain substantially complete neutralization, for all frequencies to which the circuits are tunable, the transformation ratios of transformers *T*2 and *T*3 are varied as the circuits are tuned to different frequencies and preferably simultaneously therewith. In the arrangement shown couplings 7 secured to the rotor shafts of condenser *K*2 and *K*3 engage the bent ends of shafts 8 of the movable primary coils *p*2 and *p*3 of transformers *T*2 and *T*3 to effect movement in unison of the condenser rotors and coils *p*2 and *p*3.

The number of turns or inductance of the fixed coils *P*2 and *P*3 which as shown in Figs. 2 and 3 may be wound over respective secondaries *S*2 and *S*3 is such that the mutual inductance between *P*2, *P*3, and *S*2, *S*3 respectively, is greater than that between the coils *p*2, *p*3 and *S*2, *S*3 when the latter are in maximum inductive relation so that for all positions of the rotatable coils

the radio-frequency potentials of the anodes of tubes *V*1 and *V*2 are always opposite in polarity to the potentials of the grid terminals of the associated secondaries.

The secondaries *S*1, *S*2, and *S*3 in radio apparatus capable of receiving signals having wave lengths within the broadcast range, may each comprise about 112 turns of #36 B & S gauge wire on a tubular form 9 of suitable insulating material, as bakelite, fibre, or the like, having a diameter of about 1 1/8". The primary winding *P*1 of about 13 turns of #36 B & S gauge wire is wound directly over secondary *S*1, preferably at the cathode end thereof, suitable insulation as a strip of varnished cambric, or the like, being interposed between the windings, if desirable or necessary. The fixed primary coils *P*2 and *P*3 of transformers *T*2 and *T*3 each similarly wound over the associated secondary, are of about 8 turns of #36 B & S gauge wire. Within the forms 9 of transformers *T*2 and *T*3 are disposed the rotatable supports 10 of the movable primary coils *p*2 and *p*3 in position effecting their inductive relation to the associated secondary and fixed primary coils. Preferably, the forms 10 are each provided with a groove or slot 11 in which is wound about 5 turns of #36 B & S gauge wire.

In assembling transformers *T*2 and *T*3, the rear bearing strip 12 of phosphor bronze, or other material is placed within tube 9 with the ears or lugs 13 projecting through holes in the tube which when bent against the outside thereof secure the bearing strip 12 in position to receive shaft 14 of the coil rotor 10. Thereafter the assembled rotor including form 10, and shafts 14 and 15 to which are soldered the ends of the coil wound thereon is passed through slot 16 of the secondary form 9, the shoulder 17 on shaft 14 engaging the rear bearing plate 12. The curved, front bearing plate 18 of phosphor bronze, or the like, receiving shaft 15 of the coil rotor is sprung into the position most clearly shown in Fig. 4, with lugs 19 thereof projecting into or through holes 20 of the tubular, secondary form 9. The rear face of plate 18 presses against shoulder 21 of shaft 15 to prevent rectilinear movement of the rotor. Conductors are soldered to the bearing plates 12 and 18 to effect electrical connection with the terminals of the coil wound in groove 11.

The coil and condenser rotors of each stage are mechanically connected and the electrical relation between the fixed and movable primary coils is such that when the condenser rotors are in a position effecting tuning of the amplifier input circuits to the highest wave length or lowest frequency to which they are capable of responding, the fixed and movable coils are in maximum "assisting" relation, that is the magnetic fields produced by current flowing through them are cumulative in their effect upon the secondary associated therewith. When the tuning condensers are at their minimum setting to tune the amplifier circuits to the highest frequency to which they are capable of being tuned, the fields produced by the fixed and movable coils are in maximum opposition so that only their difference is effective upon the secondary inductively related thereto. As the amplifier circuits are tuned to high and higher frequencies, the voltage-transformation ratio of the radio-frequency transformers is therefore simultaneously increased, maintaining the counter feed-back effects substantially equal and opposite to feed-back effects for all wave lengths within the range to which the circuits are tunable.

Hitherto, in tuned radio-frequency amplifiers utilizing transformers having fixed coupling, increase of resistance or resistance effects have been utilized to compensate for the increasing tendency to instability of the amplifier at the lower wave-lengths with adverse effect upon the selectivity of the amplifier. In the arrangement described by selection of proper values of the fixed and movable coils, for example, as above described, it is not necessary to use resistances or their equivalent, which simplifies the apparatus by eliminating these damping elements and improves selectivity. Further, the selectivity is maintained at a high value as the circuits are tuned to the higher frequencies since the voltage ratio of the secondary to the primary of the transformers is increased by the tuning operation.

The change in magnitude of the inherent capacities k_4 and k_5 which occurs as the position of the tuning condenser rotors is varied, is at all times in a sense which is opposite to the sense of change in the voltage-transformation ratio of the transformers T_2 and T_3 to effect stability of the amplifier at all frequencies within its tuning range.

Referring again to Fig. 1, the tubes V , V_1 and V_2 of a type having a filament adapted to be heated from an alternating current source, are supplied from the secondary 22 of a transformer whose primary 23 is connected through regulating resistance 24 and switch 25 to a source of alternating current source 26. For convenience, a plug and socket connection not shown may be utilized to connect the transformer primary to house wiring or equivalent standard power circuit. The heater h of tube V_3 is supplied from transformer secondary 27 with current from which is derived heat to render the equi-potential cathode f electron-emissive. Secondaries 22 and 28 may be utilized to supply current to other tubes not shown, for example tubes employed in audio-frequency amplifier stages.

The terminals of secondary 29 are connected to the anodes of a full wave rectifier 30 of the thermionic type having a cathode f heated by current from transformer secondary 31. Conductor 32 from the cathode of the rectifier tube 30 to the anodes of thermionic tubes V , V_1 , V_2 , etc. includes the inductances L which together with condensers C_2 , comprise a filter system for suppressing ripples of the rectified anode current. Conductor 33 from a mid-tap of secondary 29 to a mid-tap of resistance R_2 connected across filament secondary 22, includes a resistance R_3 whose low potential end is connected to earth E or equivalent. The flow of anode current through resistance R_3 produces a drop of potential which is utilized to maintain the grids g of tubes V , V_1 and V_2 negative with respect to their associated cathodes. To prevent reaction between tube circuits, particularly modulation of the radio-frequency signal energy, there is included in that portion of conductor 32 connected to the anode circuits of the detector and audio-amplifier tubes, a suitably high resistance R_4 between the anode end of which and ground is connected condenser C_3 .

What we claim is:

1. In tuned amplifiers utilizing one or more transformers, the method of stabilization which comprises utilizing inherent capacity and reversal of transformer windings to effect stability, and varying the voltage transformation ratio of a transformer as the amplifier is tuned to

different frequencies to compensate for variation in effectiveness of stabilizing capacity.

2. In tuned amplifiers utilizing one or more transformers, the method of stabilization which comprises utilizing inherent capacities and reversal of transformer windings to effect stability, and varying the voltage transformation ratio of the transformers in the same sense that the resonance frequency is changed as the amplifier is tuned from one frequency to another frequency, and to an extent maintaining substantially constant the stabilizing effect of the capacities. 80

3. In tuned amplifiers comprising one or more transformers and tuning devices, the method which comprises utilizing inherent capacities between fixed elements of the tuning devices as stabilizing capacities, adjusting movable elements of the tuning devices to adjust the amplifier to resonance from one frequency to another frequency, which adjustment affects the magnitudes of the stabilizing capacities, and varying the voltage transformation ratios of the transformers to compensate for the changes in magnitude of the stabilizing capacities. 90

4. In tuned amplifiers comprising one or more transformers and tuning devices, the method which comprises utilizing inherent capacities between fixed elements of the tuning devices as stabilizing capacities, adjusting movable elements of the tuning devices to adjust the amplifier to resonance from one frequency to a higher frequency, which adjustment decreases the magnitudes of the stabilizing capacities, and simultaneously therewith, increasing the voltage transformation ratio of the transformers to compensate for the decrease in magnitude of the stabilizing capacities. 105

5. In an amplifier of one or more stages comprising cascaded tuned circuits including transformer secondaries tuned by devices having movable elements, the method which comprises utilizing inherent capacities between elements of the circuits in a stabilizing relation, adjusting the movable elements of the tuning devices to tune the circuits from resonance at one frequency to resonance at a higher frequency, which adjustment decreases the magnitude of the natural stabilizing capacities, and increasing the voltage transformation ratios of the transformers to 115 maintain substantially constant the stabilizing effect of the capacities. 120

6. A stabilized amplifier comprising a thermionic tube, transformers in the input and output systems thereof having reversed windings, 130 tuning condensers in shunt to the secondaries of said transformers arranged so that the capacity between the condenser stators cooperates with the reversed windings to effect stability, and means to vary the transformation ratio of 135 the transformer in the output system to compensate for the change in magnitude of natural capacity between stators of said condensers effected by adjustment of condenser rotor structure. 140

7. A stabilized amplifier comprising a thermionic tube, tuned input and output systems therefor having natural capacities between elements thereof including tuning devices having adjustable elements, a transformer in one of said 145 systems having relatively reversed primary and secondary windings cooperating with said natural capacities to effect stability, said primary winding having a fixed section of inductance greater than that of a movable section, and means to 150

effect movement of said movable section to vary the transformation ratio of the transformer in a sense compensating for the changes in magnitudes of said natural capacities effected by movement of the adjustable elements of said tuning devices.

8. A multi-stage amplifier comprising thermionic tubes, input and output systems therefor tunable by condensers having adjustable elements, transformers having their primary windings in the anode circuits of said tubes and their relatively reversed secondary windings co-operating with capacities between said systems to effect stability, said capacities decreasing in magnitude as said adjustable condenser elements are varied to tune to higher frequencies and means movable simultaneously with said adjustable elements to increase the voltage transformation ratio of said transformers as said elements are tuned to higher frequencies.

9. The combination with an amplifier tube, of a capacity area connected to the control electrode thereof, a transformer whose primary is in the output circuit of said tube, a condenser for tuning the secondary circuit of said transformer and constituting a capacity area forming a stabilizing capacity with said first named capacity area, said stabilizing capacity decreasing in magnitude as said condenser is adjusted to tune to higher frequencies and means for increasing the ratio of voltage transformation of said transformer as said condenser is adjusted to tune to higher frequencies to compensate for the decrease in magnitude of said stabilizing capacity.

10. Stabilized radio-receiving apparatus comprising thermionic tubes, tuning condensers in the input circuits thereof having stator and rotor structures with inherent capacity between the stator structures which is reduced as the rotor structures are moved to tune said circuits to higher frequency, a transformer for coupling said tubes having relatively reversed windings to effect counter feed-back through said inherent capacity, and means for increasing the voltage-trans-

formation ratio of said transformer as said condensers are adjusted to tune said circuits to higher frequency to compensate for said decrease in inherent capacity.

11. Stabilized radio-receiving apparatus comprising a thermionic tube, condensers for tuning the input and output systems of said tube, said condensers being so positioned that inherent capacity exists between them, said condensers being of such structure and so disposed that said inherent capacity is reduced as the adjustable elements of said condensers are moved to tune said systems to higher frequency, a transformer in the output system of said tube having relatively reversed windings to effect counter feed-back through said inherent capacity, movable means for increasing the voltage-transformation ratio of said transformer as the adjustable elements of said condensers are moved to tune said systems to higher frequency to compensate for said decrease in inherent capacity, and means for coupling said movable means and the adjustable elements of said condensers to effect their actuation in unison.

12. Stabilized radio-receiving apparatus comprising thermionic tubes, tuning condensers having their stators connected to the control electrodes of respective tubes and so disposed that inherent capacities between the stators are reduced as the condenser rotors are adjusted to tune the input circuits of said tubes for higher and higher frequencies, coupling transformers having reversely poled windings to effect counter feed-back through said inherent capacities, and means operable in unison with said condenser rotors to change the coupling of the windings of said transformers while maintaining reversed poling thereof to increase the voltage transformation for higher and higher frequencies, and thereby to compensate for said decrease in magnitude of said inherent capacities.
